UNITED STATES PATENT OFFICE.

BYRON J. HEALY, OF KALAMAZOO, MICHIGAN.

TWO-WHEELED VEHICLE.

SPECIFICATION forming part of Letters Patent No. 372,674, dated November 8, 1887.

Application filed August 2, 1887. Serial No. 215,915. (No model.)

To all whom it may concern:

Be it known that I, BYRON J. HEALY, a citizen of the United States, residing at Kalamazoo, county of Kalamazoo, State of Michigan, 5 have invented a new and useful Two-Wheeled Vehicle, of which the following is a specification.

This invention consists in a novel adaptation and association of parts, substantially as 10 below described and claimed.

In the drawing forming a part of this specification is shown a rear elevation of a two-wheeled vehicle with parts broken away.

Referring to the letters of reference marked 15 on the drawing, C is the axle, D the thills, and r r the seat-bars or body, fulcrumed at the forward end to the thills, as heretofore. The angled levers a are pivoted to the brackets c, which project laterally from each side of the 20 body r r. The spiral spring B, beneath the body, is horizontally parallel with the axle. Each end of spring or the end of the bars u, which project beyond the ends of the spring, are pivotally attached to the free ends of the 25 lower arms of the angled levers a. The hangers i are jointedly attached to the thills at the upper end and to the other arm of the angled levers a at the lower end.

At e are shoulders or stops which the arms 30 of the angled levers a contact with, thus preventing the contraction of the spiral spring B from unduly raising the body when the seat is empty. When the body is borne down, the spring is expanded, and the angled levers and 35 spring move downward and forward on a plane parallel with the sweep of the fulcrumed body, and hence the levers a and connections are always at a proper angle to work correctly.

It will be observed that both arms of the 40 angled levers are provided with a series of adjusting-holes. By changing the lower end of the hangers from one hole to another, or the ends of the rods u from one hole to another, the leverage on the spiral spring B is changed 45 for one or two persons, or for heavy or light persons to ride. To facilitate this adjustment

it is preferable to make the hangers i in two jointedly-connected parts and to jointedly attach the rods u to the ends of the spring B, as in the drawing. If the heft in the body is unduly on one side, the stop e on the other side will prevent that side of the body from unduly rising. When the body is raised up to effect the adjustment for heavy or light persons, the stops e prevent the angled levers a and the 55 hangers i from being drawn tight by the contraction of the spring B.

Having thus described my invention, what I claim is—

1. In combination, a two-wheeled-vehicle 60 body fulcrumed at the forward end, the angled levers pivoted to said body, a spiral spring horizontal and pivotally attached to the end of the angled levers, and hangers jointedly attached to the other ends of said levers and to 65 the thills, substantially as set forth.

2. The combination of the body of a two-wheeled vehicle, the brackets provided with the stops or shoulders, the angled levers, and the horizontal spiral spring and hangers, sub- 70 stantially as set forth.

3. The combination of a two-wheeled-vehicle body, the angled levers, a spiral spring, the jointed rack, jointedly attaching the spring to the end of said levers, and the jointed hangers, the arms of said levers being provided 75 with a series of adjusting-holes, substantially as set forth.

4. In combination, a vehicle-body, the brackets having the stops, the angled levers, 80 hangers sustaining one arm of the levers, and the horizontal spiral spring, the opposite ends of which are loosely attached to the other arm of each lever, substantially as set forth.

In testimony of the foregoing I have here- 85 unto subscribed my name in presence of two witnesses.

BYRON J. HEALY.
